(57) **CLAIM**

The ornamental design for a pneumatic tool, as shown and described.

DESCRIPTION

The pneumatic tool is an air-powered device for use in construction. One end attaches to an air hose, and the other end has a hardware attachment for sawing, measuring, drilling, screwing, and nailing, etc.

FIG. 1 is an upper perspective view of the pneumatic tool showing my design.

FIG. 2 is a side view thereof;

FIG. 3 is an opposite side view thereof;

FIG. 4 is a front end view thereof;

FIG. 5 is a back end view thereof;

FIG. 6 is top view thereof;

FIG. 7 is a bottom view thereof; and,

FIG. 8 is a side view showing an attachment to the tool in broken lines.

The broken lines are presented for illustrative purposes only and form no part of the claimed design.
